Patented Oct. 23, 1917.

UNITED STATES PATENT OFFICE.

WEBB JAY, OF CHICAGO, ILLINOIS.

SUCTION-OPERATED LIQUID-FEED DEVICE.

1,244,092.

Specification of Letters Patent. Patented Oct. 23, 1917.

Application filed February 23, 1917. Serial No. 150,350.

To all whom it may concern:

Be it known that I, WEBB JAY, a citizen of the United States, residing at Chicago, in the county of Cook and State of Illinois, have invented new and useful Improvements in Suction-Operated Liquid-Feed Devices, of which the following is a specification, reference being had to the accompanying drawings, forming a part thereof.

The purpose of this invention is to provide an improved device for supplying and controlling the supply of liquid fuel to the carburetor of an internal combustion engine, of the type commonly known as "vacuum feed" device. It consists in the elements and features of construction shown and described as indicated in the claims.

In the drawings:—

Figure 1 is a diagrammatic view in the nature of an elevation of a portion of an internal combustion engine equipped with the devices constituting this invention.

Fig. 2 is a vertical axial section of the part which contains the characteristic features of the invention.

It will be understood that the internal combustion engine to be served is indicated by dotted outlines at 1 in Fig. 1, 1^a being the intake manifold. B represents the carburetor of which B¹ is the float chamber or level-controlling chamber to which the liquid fuel is conducted from the part of the structure containing the characteristic features of the invention. C is a main fuel supply tank at a low level with respect to the engine. D is a fuel receptacle at a higher level connected by the fuel supply pipe, E, with the tank, C. F is a supplemental chamber mounted fixedly with respect to the receptacle, D, and below the same, the two chambers being secured together so as to constitute a substantially unitary structure which is supported in fixed position with respect to the engine and the tank, by any convenient means and upon any convenient support, not shown. G is an exhaust connection which connects the receptacle, D, with the intake manifold for producing condition of partial vacuum in the receptacle, D. H is an atmosphere inlet pipe for admitting atmospheric pressure to the upper part of the supplemental chamber, F. J is a pipe leading from the supplemental chamber, F, to the carburetor float chamber, B¹, for supplying liquid fuel to the carburetor. K is a float in the receptacle, D, being mounted therein on a stem, K¹, which is connected at the upper end by a lever, K², with the valve, L, which controls the exhaust connection through the pipe, G, for reducing the pressure in the receptacle, D, below that of the atmosphere. The other end of the stem, K¹, is connected with a lever arm, M¹, of the valve, M, which controls a passage, N, by which the receptacle, D, discharges into the chamber, F. The lever connections from the float to the valves, L and M, respectively, are arranged so that the descent of the float operates to close the valve, M, and open the valve, L, and its rise operates to close the valve, L, and open the valve, M. The particular style of lever-connections for this purpose may be varied indefinitely. It is to be noticed, however, that the valve, L, is positioned with respect to its seat so as to be held thereon by the suction,—that is, so that the suction tends to resist the opening movement of the valve when it has once become seated; and it is also to be noticed that the valve, M, is so positioned with respect to its seat, that when it is once seated, the existence of a partial vacuum in the receptacle, D, operates to resist the opening movement of said valve, M. It is also to be noticed that the connection of the float, K, with the valve, M, by means of the stem, K¹, and the lever, M¹, of the valve, is such as to allow a limited range of movement of the float with respect to the valve without operating it when the valve is seated. The loose connection for this purpose, consisting of the spool or collar, O, on the lower end of the stem, K¹, having its flanges, O¹, O², somewhat widely separated so that the lever arm, M¹, which is slotted at m¹ for engaging the collar between the flanges is allowed considerable play as indicated, or so that the float stem, K¹, has considerable play with respect to the lever when the valve is seated and the lever is in horizontal position. For convenience of introducing the spool in the lever slot, that slot may be continued to the end of the lever which thus becomes forked. Preferably the range of actual movement of the float in the receptacle, D, is limited by means of a check nut P¹, on a depending threaded rod, P, at the upper part of the receptacle, D, the valve lever, K², having a slot, k², through which the rod, P, extends, as clearly seen in Fig. 2, and the nut being

adjustable on the rod to limit the descending movement,—that is, the movement which takes the valve, L, away from its seat.

The operation of the structure described is 5 as follows:—

The several chambers being connected up as shown and described, when the engine is in operation the suction operating through the exhaust connection, G, from the intake 10 manifold of the engine to the receptacle, D, produces a condition of partial vacuum in said receptacle which causes the liquid to be withdrawn from the low-level tank, C, and delivered into said receptacle, D, the discharge 15 charge from which through the passage, N, is at that time closed by the valve, M, which is in the first instance definitely held upon its seat by the weight of the float, K, and is subsequently further held upon its seat by 20 the atmospheric pressure admitted through the atmosphere inlet pipe, H, as soon as the condition of partial vacuum arises in the receptacle, D. The inflow of the liquid fuel continuing, the float, K, is lifted first, to the 25 limit permitted by the play of the collar, O, on the valve lever, M¹; and having reached this height, further upward movement being resisted by the atmospheric pressure on the valve, M,—or, as it might be stated, by the 30 suction operating to produce a partial vacuum in the receptacle, D,—the float will be halted at this position until the further rise of the liquid in the receptacle, D, increasing the submergence of the float, K, makes the 35 upward pressure upon the float sufficient to overcome the excess of atmospheric pressure on the valve over the diminished pressure in the receptacle, D, and open the valve, M, the weight of the liquid in the receptacle, D, being 40 of course added to the upward pull of the float for opening said valve. Such opening will occur with an instantaneous snap as the valve breaks away from its seat and the float bounds upward to the limit to which it 45 would normally have risen upon the rise of the liquid if not restrained by its connection with the valve. In such upward snap movement the float through the lever, K², carries the valve, L, to its seat, which as it approaches 50 its seat is further engaged by the suction and pulled to its seat, and being thus seated is then held quite firmly on its seat by the suction. Immediately upon the snapping open of the valve, M, there occurs an 55 interchange of atmospheric air admitted through the pipe, H, and passing up through the discharge passage, N, with the liquid passing down from the receptacle, D, through said discharge passage into the 60 chamber, F, the air bubbling through the liquid in said passage and in the lower part of the receptacle, D, and eventually, in a second or two, or in some instances almost instantaneously, the condition of partial vacuum in the receptacle, D, is destroyed, and 65 the pressure therein becomes substantially atmospheric; whereupon the liquid therein flows out freely into the supplemental chamber, F. With the falling of the level of the liquid in the receptacle, D, the float, K, tends 70 to fall, but is at first restrained by the suction holding the valve, L, to its seat; but eventually, as the liquid level continues to fall, and the float, K, becomes less and less submerged, the unsupported weight of the 75 float with its stem, becomes sufficient to pull the valve, L, off its seat against the suction. And this action, it will be observed, will also occur with a snap as the valve breaks away from its seat, and the float, K, and its stem 80 descending quickly, operates the valve, M, causing it to be seated, whereupon the suction now admitted freely past the valve, L, producing partial vacuum in the receptacle, D, further assists in holding the valve, M, 85 permanently to its seat, and the refilling of the receptacle, D, continues as at first described. It will be understood that the liquid discharged into the supplemental chamber, F, is at all times free to flow out from 90 said chamber through the pipe, J, leading to the carburetor float chamber, said chamber, F, being at all times exposed to atmospheric pressure through the pipe, H. And it will be understood that if the requirements 95 of the engine in comparison with the feeding capacity of the device are at any time such that the supply of fuel discharged into the supplemental chamber, F, is in excess of the requirements, so that the chamber, F, becomes 100 filled, that condition would eventually extend to the receptacle, D, and the float, K, would not be able to fall, but would remain at elevated position, holding the valve, L, seated, and the operation of the device would 105 cease until the withdrawal of the liquid from the supplemental chamber, F, permitted the discharge of liquid from the receptacle, D, into the chamber, F, whereupon the operation would be resumed as above described. 110 In view of the possibility of the chamber, F, being thus flooded and the liquid level rising through the passage, N, into the chamber, D, it is important that the atmosphere inlet connection to the chamber, F, should be extended at least as high as the liquid can possibly rise in the chamber, D, and the pipe, H, is so 115 shown.

It will be obvious that it is immaterial what is the nature of the liquid fed by this device and that it may be employed to supply oil for lubrication as well as to supply oil for fuel.

To facilitate seating of the valve, M, it may be mounted loosely on a centering stud, 125 m, on the lever, M¹, and retained by a cotter pin, m², the central aperture, m³, by which it is thus mounted being closed when the valve is seated, by the tapered shoulder, m⁴, at the base of the stud. 130

I claim:—

1. In combination with a main low level liquid supply tank, a liquid supply receptacle located in a plane above said tank and closed except as to the connections hereinafter indicated; a supplemental chamber connected with said receptacle for discharge of liquid by gravity from said receptacle into said supplemental chamber; a supply connection from the main tank to said receptacle, and an exhaust connection to said receptacle for reducing the pressure therein below that of the atmosphere; an atmosphere inlet connection to the upper part of said supplemental chamber; a valve controlling the communication of said receptacle with said supplemental chamber, and means in said receptacle for opening and closing said valve at pre-determined high 75 and low levels of the liquid in said receptacle.

2. In combination with a main low level liquid supply tank, a liquid supply receptacle located in a plane above said tank and closed except as to connections hereinafter mentioned; a liquid supply connection from said tank to said receptacle; a supplemental chamber, connections from said receptacle to said supplemental chamber for discharge of liquid by gravity from the receptacle into the chamber; an exhaust connection to said receptacle for reducing the pressure therein below that of the atmosphere; an atmosphere inlet connection to the upper part of said supplemental chamber; a valve which controls the discharge of liquid from the receptacle to the supplemental chamber; a float device in said receptacle and operating connections therefrom to the 100 valve for opening and closing the latter according to the height of liquid in the receptacle.

3. In combination with a main low level liquid supply tank, a liquid supply receptacle located in a plane above said tank and closed except as to connections hereinafter mentioned; a liquid supply connection from said tank to said receptacle; a supplemental chamber and connections from the receptacle to said chamber for discharge of liquid by gravity from the receptacle into the chamber; an exhaust connection to the receptacle for reducing the pressure therein below that of the atmosphere; an atmosphere inlet connection to the upper part of the supplemental chamber; a valve which controls the communication of the receptacle with the chamber, positioned so as to be assisted in opening by the gravity flow of the liquid from the receptacle into the chamber; a device in the receptacle which is operated in one direction by the accumulation of liquid in the receptacle and in the opposite direction by the withdrawal of liquid 125 from the receptacle; operating connections

from said device to said valve for positively opening and closing it, the passage which connects the receptacle with the supplemental chamber being large for free and rapid discharge of the liquid from the receptacle into the chamber, whereby it is adapted also to permit the movement of air from the chamber into the receptacle simultaneously with the movement of liquid from the receptacle into the chamber.

4. In combination with a main low level liquid supply tank, a liquid supply receptacle located in a plane above said tank and closed except as to the connections hereinafter mentioned; a supplemental chamber 80 and liquid discharge connections from the receptacle to said supplemental chamber adapted to permit discharge by gravity from the receptacle to the chamber; exhaust connections to the receptacle for reducing 85 the pressure in said receptacle below that of the atmosphere; a valve which controls the liquid discharge connection from the receptacle to the chamber; a valve which controls the connection to the receptacle; a float in the receptacle and mechanical connections by which it operates both said valves positively for closing the exhaust connection and opening the discharge connection at a high level of the liquid in the 95 chamber, and reversely operating said valves at a low level of the liquid, and an atmosphere inlet connection to the chamber at the upper part thereof for admitting air into the receptacle by way of the liquid discharge connection when the valve controlling the same is open.

5. In combination with a main low level liquid supply tank; a liquid supply receptacle located in a plane above said tank 105 and substantially closed except as to connections hereinafter mentioned; a liquid supply connection from the tank to the receptacle; a supplemental chamber and a liquid discharge connection from the receptacle to said supplemental chamber; an atmosphere inlet connection to said supplemental chamber for admitting air to the receptacle through the liquid discharge connection therefrom to the chamber; a valve which controls said discharge connection; a valve which controls the exhaust connection to the receptacle; a float in the receptacle and mechanical connections from the float to both said valves for operating them by the rising and falling of the 110 float in change of level of the liquid in said receptacle, said connections being adapted to open the discharge-controlling valve and close the exhaust-controlling valve when the float rises, and reversely operate said valves 115 when the float falls, the exhaust-controlling valve being positioned with respect to its seat for being held thereto by the suction when seated.

6. In combination with a main low level 120

liquid supply tank; a liquid supply receptacle located in a plane above said tank and substantially closed except as to connections hereinafter mentioned; a liquid supply connection from the tank to the receptacle; a supplemental chamber and a liquid discharge connection from the receptacle to said supplemental chamber; an atmosphere inlet connection to said supplemental chamber for admitting air to the receptacle through the liquid discharge connection therefrom to the chamber; a valve which controls said discharge connection; a valve which controls the exhaust connection to the receptacle; a float in the receptacle and mechanical connections from the float to both said valves for operating them by the rising and falling of the float in change of level of the liquid in said receptacle, said connections being adapted to open the discharge-controlling valve and close the exhaust-controlling valve when the float rises, and reversely operate said valve when the float falls, said discharge-controlling valve being positioned with respect to its seat for being held thereto by the suction when the exhaust-controlling valve is open.

7. In combination with a main low level liquid supply tank; a liquid supply recep-

tacle located in a plane above said tank and substantially closed except as to connections hereinafter mentioned; a liquid supply connection from the tank to the receptacle; a supplemental chamber and a liquid discharge connection from the receptacle to said supplemental chamber; an atmosphere inlet connection to said supplemental chamber for admitting air to the receptacle through the liquid discharge connection therefrom to the chamber; a valve which controls said discharge connection; a valve which controls the exhaust connection to the receptacle; a float in the receptacle and mechanical connections from the float to both said valves for operating them by the rising and falling of the float in change of level of the liquid in said receptacle, said connections being adapted to open the discharge-controlling valve and close the exhaust-controlling valve when the float rises, and reversely operate said valve when the float falls, both of said valves being positioned with respect to their seats for having their opening resisted by the suction.

In testimony whereof, I have hereunto set my hand at Chicago, Illinois, this 21st day of February, 1917.

WEBB JAY.
